CLAIM

The ornamental design for a modular strapping head, as shown and described.

DESCRIPTION

FIG. 1 is a front top right-side perspective view of a modular strapping head of our new design.

FIG. 2 is a rear bottom left-side perspective view of the modular strapping head of FIG. 1.

FIG. 3 is a right-side elevational view of the modular strapping head of FIG. 1.

FIG. 4 is a left-side elevational view of the modular strapping head of FIG. 1.

FIG. 5 is a rear elevational view of the modular strapping head of FIG. 1.

FIG. 6 is a front elevational view of the modular strapping head of FIG. 1.

FIG. 7 is a top plan view of the modular strapping head of FIG. 1; and,

FIG. 8 is a bottom plan view of the modular strapping head of FIG. 1.

The broken lines showing parts of the modular strapping head form no part of the claimed design.
